(57) **CLAIM**

The ornamental design for a light bulb, as shown and described.

DESCRIPTION

FIG. 1 is a perspective view of a light bulb showing my new design in a first embodiment;

FIG. 2 is a first side elevational view thereof;

FIG. 3 is a second side elevational view thereof;

FIG. 4 is a third side elevational view thereof;

FIG. 5 is a fourth side elevational view thereof;

FIG. 6 is a top plan view thereof; and,

FIG. 7 is a bottom plan view thereof.

The broken lines in the drawings depict portions of the light bulb that form no part of the claimed design.
